PILE FABRIC LOOM

Howard Mason, Saxonville, Mass.

Application December 3, 1931. Serial No. 578,670

5 Claims. (Cl. 139—9)

This invention relates to pile fabric looms of the type employing tube frames, and more particularly to further improvements in the construction of my Patent No. 1,845,614, granted Feb. 16, 1932, directed to mechanism for accurately positioning each tube frame relative to the fabric during the tuft inserting operation.

In the Axminster or tube frame type of loom a large number of tube frames are employed to present different colored tuft or pile yarns to the fabric in accordance with the pattern being woven. The tube frames are usually supported above the loom and are advanced in the proper order towards the weaving position by conveyor chains. As each tube frame is advanced to a predetermined position above the weaving point, it is engaged by mechanism upon the loom and transferred from the conveyor to the tuft inserting position.

Difficulty has been experienced heretofore in accurately positioning each tube frame adjacent the fabric during the tuft inserting operations, and means is shown, described and claimed in my patent above mentioned for accurately supporting each tube frame adjacent the fabric during the introduction of the tuft yarns. This is accomplished in accordance with the disclosure of said patent by mounting tube frame positioning blocks upon the front knife supporting frame so that the blocks will support each tube frame accurately in the desired position adjacent the fabric.

While the mechanism of said patent operates in a highly satisfactory manner, it may be desirable from time to time to vary the lifting action of said blocks upon the tube frame. For example, this may be desirable to level or true up the tube frame with respect to the adjacent fabric, or compensate for movement of the knife supporting frame in adjusting the knife.

The present invention therefore, resides in simple means that may be easily and quickly adjusted to vary the lifting action of said blocks upon the tube frames, and a more specific feature of the present invention resides in eccentrics or eccentric sleeves associated with the tube frame transfer mechanism and adapted to be angularly adjusted to vary the lifting action of the blocks upon the tube frames.

The various features of the invention and novel combination of parts in addition to the above will be hereinafter described in connection with the accompanying drawings which illustrate one good practical form thereof.

In the drawings:—

Fig. 1 is a side elevation of a portion of an Axminster loom provided with the novel features of the present invention;

Fig. 2 is a perspective view of an eccentric sleeve and parts associated therewith; 63,

Fig. 3 is a perspective view of one of the clutch arms and associated parts for a tube frame;

Fig. 4 is a vertical sectional view through the clutch arm and sleeves associated therewith;

Fig. 5 is a perspective view of a tube frame supported in spaced relation to the front knife carrying frame; 65,

Fig. 6 is a side view showing a tube frame supported in one position adjacent the fabric by the novel means of the present invention; and 70.

Fig. 7 is a similar view showing the tube frame supported in a second position by said means.

The improvement of the present invention may be employed in connection with any form of Axminster loom where tube frames are used in the weaving process, as distinguished from the nippertype loom. The loom illustrated in the drawings is for the main part well known in construction and operation.

In the Axminster loom shown the operating parts are supported by the spaced side frames 10, only one of such side frames being shown and each of these frames is provided with the upright column 11 adapted to support the mechanism for handling the tube frames 12, which are advanced by the conveyor chains 13 towards the weaving position in a well known manner. These chains pass downwardly from the overhead supporting structure, not shown, and pass about the sprockets 14, which may be rigidly mounted upon 90 and driven by the shaft 15, which is rotatably supported by brackets 16 projecting laterally from the columns 11.

The warp threads *a*, *b*, may be supplied from the usual let off beam in a well known manner and 95 are shifted by the harnesses 17, as usual, and the woven pile fabric *F* is advanced as woven towards the front of the loom over the fabric supporting mechanism 18.

As each tube frame 12 is advanced by the 100 chains 13 to a position directly below the shaft 15 its opposite ends are engaged in a well known manner by the clutches 19 carried by the clutch arms 20 supported by the pivotal shaft 21. The arrangement is such that the arms 20 may be 105 rocked slightly in a horizontal plane to move the clutches 19 into and out of engagement with the ends of the tube frame 12, and may be rocked in a vertical plane to convey a tube frame towards and from the tuft inserting position. The rods or 110

links 22 are provided to impart the desired tilting movement to a tube frame while it is in the lowered or tuft inserting position. Various means have been proposed heretofore for imparting the desired movements to the arms 20 and rods 22 and in the construction shown the clutch arms 20 are rocked in a vertical plane by the cams 23 secured to the operating shaft 24. These cams 23 serve to lift the pivoted levers 25, each of which has a cam engaging roller 26, and the outer end of each lever 25 is connected to an arm 20 by a link 27. Each tube frame tilting rod 22 is operatively connected to a bell crank lever 28, which is pivoted at 29 and is provided with the operating rod 30.

The operation of the mechanism just described is such that when a tube frame is engaged at its opposite ends by the clutches 19 it is moved downwardly by the downward rocking movement of the arms 20 to introduce the tubes 31 between the warp threads so as to insert the tuft yarns c between the warps, and a dipping or wiping-in motion is imparted to the tube frame at this time by the links 22 to facilitate the insertion of the yarns c downwardly between the warps. A shot of filling or weft is then inserted and beaten up against the fell of the cloth by the reed 32 supported by the reed holder or lay 33 carried by rocking levers 34 pivotally supported by the shaft 35, and while the lower ends of the tuft yarns c are held by the reed, the clutch arms 20 are raised to lift the tube frame so as to unwind from the spool or spools 36 sufficient yarn to supply the tufts for the next yarn inserting operation of this tube frame.

After a row of tuft forming yarns c has been introduced in the fabric and properly secured therein about a binding weft it is important to sever these yarns between the fabric and tube frame. This is commonly accomplished by providing the cooperating knives 37 and 38. The rear knife 37 in the construction shown is secured to the knife supporting frame 39 which is mounted upon the upper ends of the levers 40 and these levers are supported for rocking movement by the shaft 41. The front knife supporting frame 42 is secured to the upper ends of the levers 43 which are supported for rocking movement by the pivoted shaft 44. When a row of tuft forming yarns is to be severed the knife 37 is moved frontwardly by the actuating link 45 and the knife 38 is rocked rearwardly by the downwardly extending arm 46, the lower end of which is connected by a link 47 to the lever 48. This lever is provided with a roller 49 adapted to cooperate with a cam upon the shaft 24.

The mechanism so far described operates in a well known manner, and in accordance with the disclosure of the patent above cited, means is associated with the front knife supporting frame for accurately positioning each tube frame while in the tuft inserting position.

To facilitate the operation of the tube frame positioning means associated with the front knife, the cam upon the shaft 24 for actuating the roller 49 is preferably provided with the stepped portions 50 and 51, and the tube frame positioning means as disclosed in said patent, comprises the blocks 52 mounted upon the front knife supporting frame 42 and adapted to cooperate with projections or rollers associated with the clutch arms 20.

As pointed out in said patent, it is found desirable to provide means for accurately positioning

the tube frame while the first binder shot is being bound in place, and also to provide means for lifting the tube frame an accurate predetermined distance while the tuft yarns are bound to the fabric to thereby unwind the desired length of yarns from the spool carried by the lowered tube frame. This is readily accomplished by providing each block 52 with the arcuate surfaces 53 and 54 formed in stepped relation to each other and which preferably constitute small arcs, the centers of which lie at the centre of the shaft 44. The radial distance between the arcuate surfaces 53 and 54 is preferably equal to the length of the tuft yarns to be unwound from a spool 36 ready for the next tuft inserting operation of that tube frame.

The arcuate surfaces formed upon the blocks 52, in accordance with the disclosure of the above mentioned patent, cooperate with rollers associated with the clutch arms, but it is found desirable to provide means for adjusting or varying the lifting action of the blocks 52 upon the lowered tube frame and the present invention relates to extremely simple and satisfactory means to this end.

In the embodiment of the invention illustrated in the accompanying drawings each clutch arm 20 is provided at its outer end with a rigid or integral sleeve 55 which is adapted to rotatably receive a projection or stub shaft 56 that extends laterally from the outer face of the clutch 19, as best shown in Fig. 3. The arrangement is such that the projection 56 serves to support the clutch 19 upon its arm 20 for rocking or tilting movement. Upon the sleeve 55 is rotatably mounted an eccentric sleeve 57 and since it is desirable to secure the eccentric sleeve upon the sleeve 55 in different positions of angular adjustment these two sleeves are provided, in the construction shown, with co-operating annular toothed flanges which serve to prevent relative rotation between these two sleeves as long as the teeth are held in mesh with each other. The eccentric sleeve 57 is preferably provided with the outer sleeve or roller 58 adapted to turn freely upon the sleeve 57 so as to roll upon the cam surfaces 53 and 54. The parts just described are readily held in their assembled relation by the washer 59 provided at the outer end of the shaft 56 and held thereupon by the cotter pin 60, as will be apparent from Fig. 4.

The operation of the mechanism of the present invention for accurately positioning a tube frame adjacent the fabric is such that after the clutch arms 20 have been lowered, as shown in Fig. 6, to introduce the yarns c between the warps, the front knife supporting frame 42 is moved rearwardly by the cam 51 sufficiently to force the cam face 53 of each block 52 under the roller 58 to raise the tube frame to the desired predetermined position, as will be apparent from Fig. 6. After the weft has been inserted and beaten up to hold the yarns c firmly in place the knife supporting frame 42 is advanced by the cam 50 to the position in which it is shown in Fig. 7 to thereby engage the upper cam surfaces 54 with the rollers 58 to positively lift the tube frame an accurate predetermined distance. The rearward movement of the forward knife 38 may be limited by the adjustable screws 61.

In this manner the stepped surfaces 53 and 54 operate independently of the usual actuating mechanism for the arms 20 and serve to lift the lowered tube frame to one position preparatory to beating up a binding weft against the yarns c, and operate to lift the tube frame to a second posi-

tion to draw off the proper length of yarns from the tube frame.

It is found in practice that it is desirable from time to time to vary the lifting action of the blocks 5 52 upon the lowered tube frame. This may be necessary as a result of changing the shims 62 provided between the frame 42 and levers 43 to vary the adjustment of the front knife, or to level or even up the tube frame with respect to the 10 fabric, and the desired adjustment is quickly accomplished in accordance with the present invention by removing the cotter pins 60, so that the teeth of the eccentric sleeve 57 may be disengaged from the teeth upon the sleeve 55 to permit rotation of the eccentric sleeve 57 upon the sleeve 55 to 15 secure the desired angular adjustment, whereupon the parts may be reassembled and secured in place by the cotter pin 60.

The rotation of the eccentric sleeves 57 at the 20 opposite sides of the loom to the desired position of angular adjustment is facilitated by providing graduations or positioning marks 63 and 64 upon the cooperating annular toothed portions, as shown.

25 What is claimed is:—

1. In a pile fabric loom provided with tube frames, in combination, shed forming mechanism, a tube frame conveyor, clutches adapted to engage the opposite ends of a tube frame and move it from the conveyor to the tuft inserting position to supply tuft yarns to the fabric, a projection adjacent each clutch, blocks supported at the front of the loom for movement by a going part of the loom towards a lowered tube frame and adapted to cooperate with said projections to lift the tube frame adjacent the fabric to an accurate predetermined position, and an eccentric associated with each projection and adapted to be secured in different positions of angular adjustment to vary the lifting action of the blocks upon the tube frame.

2. In a pile fabric loom provided with tube frames, in combination, shed forming mechanism, a tube frame conveyor, clutch supporting arms 45 provided with clutches adapted to engage the opposite ends of a tube frame and move it from the conveyor to the tuft inserting position, projecting means upon each clutch arm, tuft yarn cutting mechanism including a knife carrying frame movable towards and from the row of inserted yarns, blocks upon the knife carrying frame adapted to cooperate with said means to lift the tuft inserting tube frame to an accurate predetermined position, and each projecting means

including an eccentric adapted to be secured to a clutch arm in different positions of angular adjustment to vary the lifting action of the blocks upon the tube frame.

3. In a pile fabric loom provided with tube frames, in combination, shed forming mechanism, a tube frame conveyor, clutch supporting arms provided with clutches adapted to engage the opposite ends of a tube frame and move it from the conveyor to the tuft inserting position, a projection upon each clutch arm, tuft yarn cutting mechanism including a knife frame movable towards and from the row of inserted yarns, blocks upon the knife frame adapted to cooperate with said projections to lift the tuft inserting tube frame to an accurate predetermined position, and an eccentric sleeve rotatably adjustable upon each projection to vary the lifting action of the blocks upon the tube frame.

4. In a pile fabric loom provided with tube frames, in combination, shed forming mechanism, a tube frame conveyor, clutches adapted to engage the opposite ends of a tube frame and move it from the conveyor to the tuft inserting position to supply tuft yarns to the fabric, a projection adjacent each clutch, blocks supported at the front of the loom for movement by a going part of the loom towards a lowered tube frame and adapted to cooperate with said projections to lift the tube frame adjacent the fabric to an accurate predetermined position, and an eccentric sleeve rotatable upon each projection and having teeth associated therewith for holding the sleeve in different positions of angular adjustment to vary the lifting action of the blocks upon the tube frame.

5. In a pile fabric loom provided with tube frames, in combination, shed forming mechanism, a tube frame conveyor, clutches adapted to engage the opposite ends of a tube frame and move it from the conveyor to the tuft inserting position to supply tuft yarns to the fabric, a projection adjacent each clutch, blocks supported at the front of the loom for movement by a going part of the loom towards a lowered tube frame and adapted to cooperate with said projections to lift the tube frame adjacent the fabric to an accurate predetermined position, an eccentric sleeve rotatably mounted upon each of said projections and adapted to be secured in different positions of angular adjustment to vary the lifting action of the blocks upon the tube frame, and a sleeve roller journaled upon each eccentric sleeve.
